UNITED STATES PATENT OFFICE.

LUTHER PATTON, OF BIRMINGHAM, ALABAMA, ASSIGNEE TO TUBE JOY PATCH COMPANY, A CORPORATION OF ALABAMA.

TIRE-PATCHING APPLIANCE.

Application filed January 24, 1927. Serial No. 163,266.

My invention relates to a tire patching appliance of a type suitable for use in connection with tubes of cementing compound used to apply rubber patches to the inner tubes of 5 automobiles or other rubber articles.

In making a "cold patch", as patches of the above type are generally termed in the trade, it is necessary that the rubber surface to be patched shall receive preliminary treatment that will insure the patch holding and that the patch when applied shall be rolled so as to force out all air pockets and insure a tight contact throughout between the patch and the prepared surface to be patched.

15 In addition to the foregoing necessary objects, it is important that the tube of cement should itself be protected so that it will not be damaged in the kit or work box, and it is of marked advantage that the tube 20 be both carried and protected by the appliance itself, so that both are always at hand for the patching operation.

With these several objects in view I have designed a tube holder of metal which provides of itself not only protection for the tube but also an abrading surface suitably positioned for convenient use, a scraping surface also most convenient for use, and in addition thereto a roller which, as a matter 30 of convenience and economical construction, is mounted on a rivet or pin which secures the front flanges of the tube holder appliance in position embracing the forward end of the tube.

35 It is a distinctive feature of my invention that the scraping surface conforms substantially with the taper at the end of a full tube of cement and that this scraping surface should terminate in a wide scraping edge 40 which projects above the top level of the mounted tube.

It is a further distinctive advantage that the body portion of the tube should be held down and also protected by bendable flanges 45 which do not interfere with the access to the tube to express all of the cement therefrom.

50 It is a further distinctive advantage that the tube shall be held in position under the bendable and the roller holding flanges, being prevented by movement in one direction by the inclined abrading surface and in the other direction by an upturned lip engaging

the front end of the tube so as to hold it in position with its end cap exposed for convenient removal and replacement. 55

My invention further comprises the various novel details of construction and arrangements of parts, which are obviously susceptible of wide variation but which in 60 their preferred embodiment only are illustrated in the accompanying drawings which form a part of this specification, and in which:—

Fig. 1 is a plan view of my improved appliance. 65

Fig. 2 is a side view; and

Fig. 3 is a bottom view of Fig. 1.

Fig. 4 is a front end view of Fig. 2.

Similar reference numerals relate to similar parts throughout. 70

In the embodiment of my invention illustrated, I show the appliance as comprising a semi-tubular body portion 5, preferably formed by a metal stamping, which corresponds substantially to the shape of the tube 6 of cement which is intended to be received therein. This tube corresponds to the usual type of cement tube now on the market and is provided at its forward end with a threaded nipple 7 closed by a screw cap 8. At its other end 9 the sides of the tube converge and are joined together. The main body portion 5 of the appliance is provided at its forward end with two flanges comprising 75 curved portions 10 and upright ends 11, the curved portions forming a continuation of the curved bottom of the body 5 and the ends 11 forming vertical spaced parallel walls which receive a rivet or pin 12 on 80 which a flat faced roller 13 is mounted free to rotate. This roller is preferably mounted near the upper front corners of the ends 11 so that its periphery is exposed both above and to the front of the appliance. A 85 lip 14 at the bottom of the front end of the body 5 is bent up so as to engage the slightly tapered front end 15 of the tube 6 and hold the tube from slipping out forwardly through the appliance and yet leaving its 90 cap 8 exposed and its nipple end clear of the appliance so that the cement, as expressed therefrom, can be applied to the surface to be treated. 95

Substantially midway of the body portion 105 I provide a pair of bendable flanges 16

which are formed in upright position and after the tube is in place are bent down over it, as shown in Fig. 1, thus holding it in the appliance while leaving the major portion 5 of the tube's body exposed so that by pressing upon it the contents of the tube can be forced out.

Inasmuch as the tube 6 tends to widen as it approaches its flat end, so the body 5 of the appliance flares in substantial accordance with the tube and is thus provided with divergent side edges 17. In like manner the body portion 18 at the rear end of the tubular body is sloped up at an angle 15 of approximately 45° and conforms substantially to the angle of the base of the tube and this surface is provided with roughened serrations or spuds 19 which are distributed over it so as to provide an effective scraping 20 means for removing grease, dirt and foreign matter from the surface to be patched. At the rear end of this inclined portion 18, I provide a further plane extension 20 which is inclined slightly rearwardly from vertical plane and which projects above the level of the tube in the appliance. The walls 17 forming the side of the rear end of the appliance have their upper edges rising at an incline towards and joining the side 25 edges of the scraper extension 20 but they leave about half of the scraper blade standing clear above them. In other words, these sides extend approximately to the top level of the tube and this with the flanges 10 and 30 16 afford all needed protection for the body of the tube against being punched or being compressed by other appliances when loose in a tool box.

Having constructed the appliance in the manner described and assembled the tube 40 therein in the manner clearly illustrated in the drawings, my device is employed in the following manner in connection with the making of a patch. First the instrument is 45 grasped in the hand with the index and middle fingers pressing against the surface 20 and in this position the abrading surface 18 is conveniently held to be worked over a horizontal surface. The rubber surface to be patched is then thoroughly scraped and abraded by the surface 18 and when it has 50 been cleaned in this manner the appliance is reversed in the hand, the cap 8 is removed and with the thumb pressing upon the rear 55 end of the tube the cement is forced out and applied to the treated surface. The cap is then applied to the tube, the holder is reversed and inverted and with the fore finger bearing on the back of the scraper 20 the 60 cement is spread over the surface and then

the surplus cement is scraped away. The patch is then applied to the cemented surface, the holder is again reversed and inverted and with the fore finger pressing on the bottom of the holder adjacent to the lug 65 14, the roller 13 is in convenient position to be pressed upon and rolled back and forth over the patch so as to insure complete adhesion of same throughout.

In the manner thus described the appliance 70 comprises in itself all of the necessary facilities for making the patch in the most effective manner.

Though I have described with great particularity the details of the embodiment of 75 the invention herein shown, it is not to be construed that I am limited thereto, as changes in arrangement and substitution of equivalents may be made by those skilled in the art without departing from the inven- 80 tion as defined in the appended claims.

Having thus described my invention, what I claim as new and desire to secure by Letters Patent, is:—

1. An appliance of the character de- 85 scribed, comprising a trough-like body shaped to receive a tube of cement, said body having side and end flanges adapted to hold such a tube in position therein with its cap end projecting and its body sufficient- 90 ly exposed to permit its contents to be pressed out.

2. An appliance as described in claim 1, in which the side flanges are freely bendable to permit of the insertion of the tube in the 95 body.

3. An appliance as described in claim 1, in which the end flanges comprise a lip at the top end of the tube and a sloping roughened surface at the bottom end of the tube. 100

4. An appliance of the character de- 105 scribed, comprising a body shaped to receive and partly enclose a tube of cement, said body having a sloping roughened end wall conforming substantially to the flat- tened end of the tube and terminating in a straight scraper edge, and means to hold the tube in said body.

5. An appliance of the character de- 110 scribed, comprising a body shaped to receive and partly enclose a tube of cement, flanges at one end of the body adapted to overhang the top end of the tube, and a roller pivot- ally mounted on said flanges.

6. An appliance according to claim 5, in 115 which said flanges are pivotally connected by a bearing pin for the roller that is inter- posed between them.

In testimony whereof I affix my signature.

LUTHER PATTON.
